UNITED STATES PATENT OFFICE.

NEIL E. SALSICH, OF BETHLEHEM, AND CHARLES A. ALDEN, OF STEELTON, PENNSYLVANIA.

TONGUE SWITCH FOR T RAILS.

Application filed August 10, 1921. Serial No. 491,297.

To all whom it may concern:

Be it known that we, NEIL E. SALSICH and CHARLES A. ALDEN, citizens of the United States, and residing at Bethlehem, Northampton County, and Steelton, Dauphin County, State of Pennsylvania, respectively, have invented certain new and useful Improvements in Tongue Switches for T Rails, of which the following is a specification.

This invention relates to a tongue switch for railway rails. The object of the invention is to provide a switch structure which is simple, strong, efficient and lasting embodying T-rail sections secured together in proper relation by a number of interjacent spacing members and by bolts passing through them, one of the spacing members acting as a support for the heel of the switch tongue both vertically and horizontally and having end spacing portions on opposite sides of a transverse line at the heel bolted to the rails. This last mentioned member being subject to great strains and wear in use is made from a superior grade of metal such as manganese steel. The invention also embodies means for holding the switch tongue in proper working position including a part movable to compensate for wear held against upward movement by sliding contact at its edges with finished rolled surfaces on the under side of the heads of adjacent rails with such operative connection to the tongue as to cause it to function as a holding down device for the tongue. Other novel features will be apparent from the following description and claims taken with the accompanying drawings. In the drawings:

Fig. 1 is a plan view of a switch structure embodying the invention;

Fig. 2 is a vertical longitudinal section on the line 2—2 of Fig. 1 through the heel portion of the tongue and the adjacent parts of and in the manganese steel spacing member;

Fig. 3 is a horizontal section on the line 3—3 of Fig. 2;

Fig. 4 is a cross section on the line 4—4 of Fig. 1 and also Fig. 3;

Fig. 5 is a perspective view of the manganese steel spacing member;

Fig. 6 is a cross section on the line 6—6 of Fig. 1 showing the end portion of the manganese steel member, the two railway rails

and a separate spacing member between one railway rail and the guard rail;

Fig. 7 is a cross section on line 7—7 of Fig. 1; and

Fig. 8 is a plan view of the manganese steel spacing member.

The embodiment of the invention shown for purposes of illustration includes the track rail 10 passing along and properly spaced from the guard rail 11 and the diverging track rail 12 joining the switch mechanism at its end. The track rail 10 and guard rail 11 are spaced apart and held in proper relation from the point of the tongue to a point near the heel by a series of spacing members which may be composed of inferior metal such as cast iron and which are so shaped in section as to fit and bear against the adjacent rails in contact with the under surfaces of their heads and the upper surfaces of the bottom flanges with their upper surfaces between the facing edges of the two rails depressed to a transverse plane below said heads to serve as a supporting surface for the tongue at that point permitting free lateral movement thereof. One of these spacing members at the end of the tongue is shown at 13 in Fig. 7 and other similar spacing members of proper size and shape to properly fit and space the rails are placed at the points marked 14 and 15 in Fig. 1. Bolts 18 pass through the vertical flanges of the rails at proper intervals through or adjacent to the spacing members to rigidly secure and adjustably clamp the rails and spacing members together in proper relation. One of these bolts and its operative relation to the parts is shown in detail in Fig. 6.

As heretofore stated, the manganese steel member shown separately in Figs. 5 and 8 and which may as a whole be designated 16, has portions which serve to space the track rail 10 and guard rail 11 adjacent the heel of the tongue on opposite sides of that heel longitudinally of the rails and also a portion spacing the diverging track rail 12 from track rail 10 where rail 12 joins the switch mechanism and it will be noted by reference to Fig. 6 that where the guard rail 11 overlaps the entering end of the diverging rail 12 there is a spacing member

17 of inferior metal such as cast iron interposed between them and the three rails with their interposed spacing members are secured and clamped rigidly together by one of the bolts 18. This produces a strong and lasting structure with the manganese steel member lapping or extending to opposite sides of the connection of the diverging rail. The tongue 19 rests on the upper surface of 10 the spacing members at intervals from its heel end to its point and may, of course, be moved laterally on a pivot at its heel to bring its point against or removed from track rail 10. The heel end of the tongue is 15 semicircular in section with its upper surface in the same straight longitudinal plane as the balance of the tongue and it has formed thereon a downwardly extending pin 20 of a diameter about equal to the width of 20 the tongue on the line of the pin the surface on the outer face of said pin being cylindrical and in effect a vertical continuation of the semicylindrical heel end of the tongue and its lower end is on a plane parallel to 25 the upper and lower surfaces of the tongue. The inner side of pin 20 facing the point of the tongue is circular in section but tapers inwardly and upwardly of the pin, as shown in Figs. 2 and 3. The lower end of the pin 30 rests on a portion of the manganese steel member 16 between its ends and the pin is so engaged by said member and cooperating parts carried by it as to support and securely so hold it and the attached tongue as 35 to prevent upward, lateral or longitudinal movement aside from its turning movement on the pin and is adapted to be adjusted to take up any looseness developed by wear; but in order to clearly understand how this is 40 done a more detailed consideration of the structure and operation of member 16 is necessary.

The manganese steel member 16 is formed as a one piece casting having an end portion 45 21 so shaped and of such cross sectional size as to fit along its edges the facing sides of track rail 10 and guide rail 11 along the under surfaces of their heads and the upper surfaces of their base flanges serving to 50 space the rails and with its flat upper surface in the plane of the upper surfaces of the other spacing members 13, 14 and 15 so that the tongue rests on it. It is provided with a transverse bolt hole and is secured and clamped to the rails by one of the bolts 55 18. A bottom plate or wall 22 of material length connects end portion 21 to the other end portion 23 of member 16 fitting along its transversely inclined margins on the bottom flanges of rails 10 and 11 and since its upper surface is materially below the upper surface of the portion 21 a vertical transverse wall or abutment 24 is formed at the plane where they join. The portion 23 is 60 materially longer than 21 and has longitudi- nal side extensions 25 and 26 fitting and spacing rails 10 and 11 respectively, the extension 25 making contact with track rail 10 extending throughout the full length of the portion 23 but extension 26 terminating 70 on the cross plane where the end of the diverging track rail 12 joins the member. Beyond that cross plane there is a longitudinal side extension 27 on the same side as 26 so spaced from extension 25 as to fit along 75 the side of the diverging rail 12 serving with the opposite part of extension 25 to space the track rails 10 and 12. The portion 23 of the manganese steel member 16 has an elevated surface 28 along its central portion 80 on the plane of the top of the rails and the tongue having flange grooves between it and rails 10 and 11. The width of this elevated portion where it joins the heel of the tongue is the same as that of the heel portion and 85 there is a central semicylindrical recess or socket 29 formed in the end of said elevated portion extending from its upper surface down to plate 22 partly between the ends of extensions 25 and 26 which terminate in a 90 transverse plane through the center line of said cylindrical portion. The semicircular heel end of the tongue and the outer face of its pin 20 fit in said semicircular recess or 95 socket with the upper surface of the tongue in the same plane as the surface 28 and the lower end of the pin resting on the bottom plate or wall 22. In the space between the tongue 19, bottom plate 22, upwardly projecting wall 24 and pin 20 two movable 100 blocks 30 and 31 are mounted. The block 30 enters the space laterally through an opening 32 in the upright flange or section of guard rail 11 with one edge in contact with wall 24 and its other edge facing block 105 31 inclined towards that wall from its outer end inward. Block 31 has one edge inclined to match and fit the inclined edge of block 30 but its opposite edge facing the pin 20 has a recess semicircular in section tapered 110 in conical form upward from its bottom closely fitting the matching tapered portion of pin 20. Block 30 moves laterally and by a wedging action moves block 31 longitudinally towards pin 20. Block 31 cannot move 115 laterally or upwardly because it has longitudinally and upwardly extending parallel side portions or ridges 33 and 34 with smooth upper surfaces closely fitting the finished rolled under surfaces of the heads 120 of rails 10 and 11 permitting only longitudinal sliding movement along those rails towards or from the pin. The means for forcing wedge block 30 inward to adjustably move block 31 towards the pin includes a 125 bolt 35 passing laterally through openings 36 and 37 at the inclined ends of these blocks with the head of the bolt resting against block 31 and the other screw threaded end projecting beyond the outer end of block 30 130

and there provided with an easily accessible screw threaded nut 38 for adjustment. Since the engagement of its ridges 33 and 34 with the under surface of the rail heads holds it down and prevents upward movement, it will be seen that side pressure forcing it against the pin will not only force it into tight contact with the surface of the semicircular recess which it fits and compensates for and take up any looseness of the pin in its bearing due to wear but will by reason of the tapered form of the contacting surfaces of the pin and block tend to move the pin and the attached tongue downward and the leverage from the opposite lower edge of the pin resting on plate 22 will make this tendency greatest on the tongue point side and it will thus serve as a holding down device for the tongue.

The upper surface 28 of the portion 23 of the manganese steel member 16 is reduced in transverse section a short distance from the semicircular recess 29 being contracted on the side next to the guard rail 11 where the diverging track rail 12 joins it and as shown, this contraction is in a curved line and is sufficient to receive the end of rail 12 correspondingly curved in section at its end with the side of its head next to the guard rail in line with the side of the full width portion and from that point to the end the side of portion 28 fits the head of rail 12 next to track rail 10. As shown in the drawings, the upper surface of portion 28 outside of the plane of contact with vertical wheels may be slightly elevated.

From the foregoing, it will be apparent that we provide a built-up switch construction as contra-distinguished from a single cast unit. Our construction consists of an ordinary main rail 10 which extends beyond the ends of the construction, a second main rail 12 which terminates at an intermediate point, and a guard rail 11. The main rail 10 and the guard rail 11 are bent or offset oppositely to provide clearance for the switch tongue 19. The main rails 10 and 12 and the main rail 10 and the guard rail 11 are spaced apart by the spacing and supporting member 16, which has a terminal spacing portion 21 to fit between the main rail 10 and the guard rail 11, an intermediate spacing portion defined by the edges 25 and 26 to fit between the main rail 10 and the guard rail 11, and a second terminal portion defined by the edges 27 and 25 and which fits between the main rails 10 and 12. Each of the spacing portions referred to fits against rail webs and is provided with transverse and horizontal openings registering with similar openings in the webs and through which the bolts 18 pass to hold the construction together.

The sides of the terminal spacing portion 21 and of the intermediate spacing portion

are aligned and converge to fit the convergent space between the main rail 10 and the guard rail 11, whereas the edge 27 of the other terminal spacing portion is offset to provide space to receive the end of the main rail 12. The latter terminal spacing portion spaces the main rails; and, preferably, a spacing member 17 is arranged at the opposite side of the main rail 12 to space the latter from the guard rail 11. Bolts 18 pass through the webs of the three rails and the spacing members 16 and 17 to hold the structure rigidly together at one end.

The spacing and supporting member 16 is provided with an elevated portion which abuts the end of main rail 12 and which has a wheel-thread surface in alignment with that of the main rail 12. As already referred to, the spacing and supporting member 16 has a vertical concave face 29 at one end of the elevated tread portion which fits a convex surface at one end of the switch tongue 19, the latter having a tread surface adapted to align with that of said elevated portion. At its other end, the tongue is shaped to fit the offset side surfaces of the main rail 10 and the guard rail 11.

From the foregoing, it will be apparent that the parts, such as the tongue 19 and the spacing and supporting member 16, particularly the elevated tread portion thereof, which are submitted to excessive strains or wear, may be made of relatively harder steel such as manganese steel. Since only the tongue and the elevated tread portion of the supporting and spacing member are provided with wheel-tread surfaces, the remainder of the wheel tread surfaces being provided by rolled rails of the ordinary type, it will be obvious that the problems of casting and machining are greatly simplified, particularly when our device is compared to cast units common in the art; and, when it is considered that manganese steel is very difficult to machine it will be apparent that the reduction of machining afforded by our construction is advantageous.

While one specific embodiment of the invention is shown for purposes of illustration, it will be understood that it is not in its broad features limited to that form beyond what is called for by the terms of description in the claims.

Having thus described the invention what is claimed as new and desired to be secured by Letters Patent is:

1. In a tongue switch, the combination with a track rail and a guard rail of a tongue having a downwardly extending pin at its heel end, a pin engaging member movable longitudinally of said rails and having sliding contact with the adjacent under surfaces of the heads of said rails on the side of the pin next to the point of the tongue preventing upward movement of said mem-

1. member, means for adjustably moving said member against said pin the operative connection between said member and pin being such that said member will act as a holding down device for the tongue in addition to compensating for wear.
2. In a tongue switch, the combination with a track rail and a guard rail of a tongue having a downwardly extending pin at its heel end, a rail spacing and heel supporting and engaging member made of a superior grade of steel rigidly secured to said rails on opposite sides longitudinally of said heel and embodying means for supporting said heel and maintaining it in proper operative position both vertically and horizontally.
3. In a tongue switch, the combination with a track rail and a guard rail of a tongue having a downwardly extending pin at its heel end, a rail spacing and heel supporting and engaging member made of a superior grade of steel rigidly secured to said rails on opposite sides longitudinally of said heel and embodying means for supporting said heel and maintaining it in proper operative position both vertically and horizontally and carrying means for so adjusting the contact and bearing surfaces as to compensate for wear in use.
4. In a tongue switch the combination with a tongue adapted to lie between a track rail and a guard rail having a straight line top surface to and including its heel end, an integral downwardly extending pin at said heel end, the said heel end of said tongue and the corresponding side of said pin being semicylindrical with its vertical axis on the center line of said tongue of a supporting member adapted to fit between said rails composed of high grade steel embodying a portion with a semicircular recess in its end fitting and abutting the semicircular heel end of the tongue and the outer face of the pin with its upper surface in the plane of and constituting a continuation of the upper surface of the tongue, an integral bottom plate extending under and materially beyond said pin and serving as a support for its lower end, an integral upwardly extending wall on said plate a material distance from said pin with its upper surface so positioned as to support the tongue and adjustable means including a tapered surface matching the tapered surface of said pin between said wall and pin cooperating therewith for forcing said pin into close contact with said member in said semicircular recess to compensate for wear and tending to hold it and the tongue down, said supporting and spacing member including main and guard rail spacing portions.
5. In a tongue switch the combination with a track rail and a guard rail of a tongue having a straight line top surface to and including a heel end semicircular in form transversely and an integral downwardly extending pin at said end, the outer face of which is semicylindrical on the lines of said heel end and the inner face of which is tapered inwardly from the lower end, of a supporting member composed of high grade steel embodying a portion with a semicircular recess in its end fitting and abutting the inner face of which is tapered inwardly from the lower end, of a supporting member composed of high grade steel embodying a portion with a semicircular recess in its end fitting and abutting the semicircular heel end of the tongue and the outer face of the pin with its upper surface in the plane of and constituting a continuation of the upper surface of the tongue, an integral bottom plate extending under and materially beyond said pin and serving as a support for its lower end, an integral upwardly extending wall on said plate a material distance from said pin with its upper surface so positioned as to support the tongue, a wedge block movable laterally in contact with said wall between its top and bottom, a pin engaging block between said wedge block and pin engaged by said wedge block and movable thereby towards said pin and having a semicircular recess in its forward side fitting and engaging the inner surface of said pin and means for moving said wedge block laterally.
6. In a tongue switch the combination with a track rail and a guard rail, a tongue having a straight line top surface to and including a heel end semicircular in form transversely and an integral downwardly extending pin at said end the outer face of which is semicylindrical on the lines of said heel end and the inner face of which is tapered inwardly from the lower end, of a supporting member composed of high grade steel embodying a portion with a semicircular recess in its end fitting and abutting the inner face of which is tapered inwardly from the lower end, of a supporting member composed of high grade steel embodying a portion with a semicircular recess in its end fitting and abutting the semicircular heel end of the tongue and the outer face of the pin with its upper surface in the plane of and constituting a continuation of the upper surface of the tongue, an integral bottom plate extending under and materially beyond said pin and serving as a support for its lower end, an integral upwardly extending wall on said plate a material distance from said pin with its upper surface so positioned as to support the tongue, a wedge block movable laterally in contact with said wall between its top and bottom, a pin engaging block between said wedge block and pin engaged by said wedge block and movable thereby towards said pin and having a semicircular recess in its forward side fitting and engaging the inner surface of said pin and means for moving said wedge block laterally.
7. In a tongue switch the combination with a track rail and a guard rail, a tongue having a straight line top surface to and including a heel end semicircular in form transversely and an integral downwardly extending pin at said end the outer face of which is semicylindrical on the lines of said heel end and the inner face of which is tapered inwardly from the lower end, of a supporting member composed of high grade steel embodying a portion with a semicircular recess in its end fitting and abutting the inner face of which is tapered inwardly from the lower end, of a supporting member composed of high grade steel embodying a portion with a semicircular recess in its end fitting and abutting the semicircular heel end of the tongue and the outer face of the pin with its upper surface in the plane of and constituting a continuation of the upper surface of the tongue, an integral bottom plate extending under and materially beyond said pin and serving as a support for its lower end, an integral upwardly extending wall on said plate a material distance from said pin with its upper surface so positioned as to support the tongue, a wedge block movable laterally in contact with said wall between its top and bottom, a pin engaging block between said wedge block and pin engaged by said wedge block and movable thereby towards said pin and having a semicircular recess in its forward side fitting and engaging the inner surface of said pin and means for moving said wedge block laterally.

fitting and rigidly secured to said rails on both sides of said line so constructed as to pivotally support said pin and means carried by said last mentioned members for adjusting the pivot connection of said tongue and preventing upward movement of the tongue.

12. In a railway switch construction, the combination of first and second converging main rails, the first of which extends throughout the construction and the second of which terminates at an intermediate point, a guard rail, a member for spacing the first and second main rails and having a portion arranged contiguous to a terminus of said second main rail and having a wheel-tread bearing surface in alignment with the wheel-tread bearing surface of said second main rail, said member extending between and spacing the guard rail and the first main rail, and a tongue member pivoted to the first member adjacent to said portion and having its upper surface in alignment with the wheel-tread bearing surface of said portion, said tongue extending between the guard rail and the first main rail.

13. In a switch construction, a supporting and spacing member having terminal and intermediate spacing portions and a portion extending above the spacing portions and having an end intermediate the ends of the supporting and spacing member and provided with an upper wheel-tread bearing surface.

14. In a switch construction, a supporting and spacing member having terminal and intermediate spacing portions, and a wheel-supporting portion extending above the intermediate and one of said terminal spacing portions, the end face of the wheel-supporting portion and said intermediate spacing portion opposite to the other terminal spacing portion being concave.

15. In a switch construction, a supporting and spacing member having a spacing portion at one end and an intermediate spacing portion connected by a bottom plate portion, a spacing portion at the other end of the member and narrower than the spacing portion at the first end or the intermediate spacing portion, and a wheel-supporting

portion extending above the spacing portions.

16. In a switch construction, a spacing member having an end spacing portion provided with converging sides, an intermediate spacing portion provided with converging sides aligned with the converging sides of said end spacing portion, and a spacing portion at the other end of the member having sides converging in the same direction as the sides of the first end portion and the intermediate portion, said last-named end spacing portion having one of its sides in alignment with one side of the intermediate portion and with one side of the first end portion and having its other side offset inwardly with respect to the corresponding side of the intermediate portion.

17. In a switch construction, a spacing member for main and guard rails having an end and intermediate guard and main rail spacing portions provided with converging and aligned lateral faces, an end spacing portion for main rails having one lateral face in alignment with a face of the intermediate portion and having the other lateral face offset inwardly of the member with respect to the corresponding lateral face of the intermediate spacing portion.

18. In a switch construction, the combination of two main rails and a guard rail, arranged side by side and the main rail intermediate the other main rail and the guard rail terminating intermediately of the construction, a spacing and supporting member having a spacing portion between the main rails and a spacing portion between a main rail and the guard rail, said member also having a wheel-tread portion abutting said terminus of a main rail, a tongue having an upper wheel-tread surface and having one end abutting said portion and the tongue extending between the main and guard rails, said end of the tongue having a downwardly extending pivot pin, and said member having bearing and supporting surfaces for the tongue and pin.

In testimony whereof we hereunto affix our signatures.

NEIL E. SALSICH.
CHARLES A. ALDEN.
